UNITED STATES PATENT OFFICE

NOAH S. HARTER, OF WAUKEGAN, ILLINOIS

FENCE MAKING MACHINE

Application filed April 17, 1930. Serial No. 444,928.

The invention relates to fence making machinery and has reference more particularly to improvements in mechanism for forming a wire fence picket.

A wire fence of the chain link or mesh type as generally constructed consists of individual links or pickets extending substantially transversely of the fabric and interlinked with adjacent pickets. As usually formed the individual pickets are in the shape of a flattened spiral, which when interlinked with adjacent pickets forms a fabric of diamond shaped mesh. The diamond mesh fabric may have when originally formed, axes transversely and longitudinally of the fabric which are substantially equal, but under conditions in actual use, the fabric will be stretched so that the longitudinal axes increase in length and the transverse axes correspondingly reduce in length. This type of wire fence is therefore unsuited for use under conditions where severe strain will be placed upon it.

The present invention contemplates a novel form of wire fence picket which, when fabricated into fencing will form a fabric of triangular mesh. This type of mesh consists of diagonal portions joined by substantial horizontal portions, whereby longitudinal strain placed upon the fabric will be taken up by horizontal portions, and thus tendency to elongate in directions parallel to these portions will be materially reduced.

To this end an object of the present invention is to provide ways and means of forming a wire fence picket of the novel type described, and of performing similar wire bending operations.

A still further object of the invention is to provide novel fence making machinery which will be simple in construction and positive and reliable in operation.

In the drawings, which illustrate an embodiment of the device:

Figure 1 is a plan view of a portion of wire

fence making machinery constructed in accordance with the present invention;

Figure 2 is a side elevation of the same;

Figure 3 is an end view of the same looking towards the right as in Figure 1;

Figures 4, 5 and 6 are plan views showing various steps in the operation of the mechanism for forming the wire fence picket;

Figure 7 shows a portion of a wire fence picket formed by the mechanism of the present invention; and

Figure 8 shows a modified form of wire fence picket also formed by the mechanism of the present invention.

Referring to the drawings, particularly to Figure 3, the present mechanism is shown as including a plurality of base members 10 supporting a plurality of vise members 11 by means of securing bolts 12. The vise members are adapted to hold in rigid position a spiral member designated in its entirety by 14. Located within the spiral is an arbor 15, which is adapted to have rotation within the spiral and for this purpose has its right hand end, as viewed in Figure 1, located in slot 16 provided in the driving shaft 17. Any suitable form of power may be associated with the driving shaft to impart rotary movement thereto. The spiral 14 is a built-up member consisting of two spiral elements and includes a tubular member 18 having one end cut into spiral shape, the threads thereof being designated 20. Associated with these spiral threads is a second spiral member having threads designated 21, the second member being so located with reference to the threads 20 as to form spiral grooves or openings 22, the purpose of which will be presently described.

A continuous length of wire 23 is fed to the arbor 15, the wire being first passed through a series of straightening rolls 24, located on a base 25. In the operation of the mechanism as rotations are imparted to the shaft 17, the wire strand 23 is fed to

the arbor at several points, the change in feed being effected at predetermined periods during the rotation of the arbor 15. For accomplishing this change of feed of the wire strand, the disk 26 mounted on shaft 17 is provided with a cam race 27. A cross shaft 28 mounted in bearings 29 is provided with an upstanding arm 30 having a pin 31 adapted to ride within the cam race 27. The arm 32 located on the other end of the cross shaft 28 is provided at its upper end with a pin 33, which has connection with the lever 34, the lever in turn being pivotally secured at 35 to arm 36. The arm 36 is rotatably mounted on pin 37 which pin is secured to base 38 formed integrally with one of the vise members 11. On the outer end of arm 36 is located a depending pin 40 adapted to have contacting engagement with the wire strand 23 immediately prior to the feeding of the same to the arbor 15. As previously stated the location of the feed of the wire strand to the arbor is changed once in every revolution of the arbor, which is accomplished by the depending pin 40 through oscillating movements imparted to the arm 36. The timing of these movements and thus the variations in the location of the feed of the wire strand to the arbor is controlled by the specific formation given to the cam race 27.

It is to be noted that the width of the arbor 15 determines the length of the horizontal portions formed in the wire picket, while a certain thickness is imparted to the wire picket by reason of the thickness of the arbor. Also, as will be more fully explained, the diagonal portions of the picket which serve to connect the horizontal portions is accomplished by the variation in the location of the point at which the wire strand is fed to the arbor.

In order to more fully understand the novel features of the present invention, attention is directed to Figures 7 and 8 of the drawings, which show the characteristic shape of the wire picket formed by the present mechanism. The horizontal portions 6 are connected by bends 7 to diagonal portions 8 which serve to form a triangular shaped mesh when the various pickets are interlinked with their adjacent pickets. By the mechanism described, the portions 6 may be formed horizontally, as shown in Figure 8, or may have a slight displacement from the horizontal as more particularly shown in Figure 7.

In the operation of the device, reference being had to Figures 4, 5 and 6, the arbor 15 is shown in a vertical position and adapted to have rotation in a direction as indicated by the arrow. The pin 40, although having contacting engagement with the wire strand 23 is at this particular position of the arbor located in its extreme left hand position. With the parts in this position, it will be

noted that one of the bends 7 between the horizontal and diagonal portions is just being completed. Referring more particularly to Figure 5, it will be seen that the arbor 15 has been rotated 90° from its position in Figure 4 and is now located in a substantially horizontal position. Also, the pin 40 is still located in its extreme left hand position, but it will be seen that by reason of the rotation of the arbor 15, the spiral member remaining stationary, the wire picket has moved a distance on the arbor equal to one quarter of the pitch of the spiral member 21, namely from point *a* to point *b*. It is during the next 90° movement of the arbor that movement is imparted to the pin 40, which thus locates the pin adjacent the right hand end of the spiral 21 at point *c*. This effects a material change in the position at which the wire strand 23 is fed to the arbor 15 and thus causes the formation on the wire picket of the diagonal portion 8. The magnitude of this diagonal portion is determined by the change in location of the feed of the wire strand 23 to the arbor 15, caused by movement of the pin 40 in addition to the movement of the picket itself upon the arbor due to rotation of the arbor which will equal substantially one quarter of the pitch of the spiral member, or the distance from point *b* to *d*.

Upon continued rotation of the arbor 15, the bend 7 being formed in the picket as shown in Figure 6, will have moved from the point *c* to point *e* during which movement of the arbor the pin 40 is retracted so that the combined effect of the movement of the picket on the arbor 15 and the rearward movement imparted to the pin 40 will form on the picket the horizontal portion 6. During the next 90° movement of the arbor another of the bends 7 in the picket is formed whereupon the parts will assume the same position as disclosed in Figure 4 and the series of operations will be again repeated. It is to be noted that the horizontal portions 6 of the picket are formed as the pin 40 is being retracted, but in combination with this movement of the pin the picket is also being caused to move in a left hand direction upon the arbor 15 by reason of the engagement of the bends 7 which have been formed with the threads of the spiral member 21. By a variation in the timing of the movement imparted to the pin 40, the portions 6 on the picket may be given a slight angular displacement from the true horizontal which will result in the formation of a picket as disclosed in Figure 7.

Although the operation of the mechanism has been described in connection with figures showing only skeleton parts of the machine, the operation of the complete device as shown in Figure 1 is similar except that the spiral member employed presents spiral openings 22 within which is located the various bends

formed on the picket. By rotation of the arbor and thus the picket they serve to cause movement of the picket upon the arbor in a direction towards the left.

5 The periodic movement of the lever 36 and thus pin 40 is caused by the contour of the cam race 27. The disk 26 and arbor 15 are both associated with shaft 17 which results in a complete cycle of movement being imparted to arm 36 during every revolution of the arbor. There is formed upon the arbor then for every revolution a horizontal portion 6, a bend 7 and a diagonal portion 8. It was previously stated that for a slight 15 displacement of the horizontal portion it was only necessary to vary the timing in the movements imparted to the arm 36. This can accordingly be accomplished by replacing the disk 26 by a similar disk having a cam race of a slightly different contour.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

30 1. A fence making machine comprising a stationary spiral member and a rotating arbor located within said member, said arbor being adapted to have a wire strand wound thereon and means for varying the location 35 of the point of feed of the wire strand to said arbor to thereby impart a characteristic shape to the wire wound upon the arbor.

2. A fence making machine comprising a stationary spiral member and a rotating arbor located within said member, means for directing the feed of wire to said arbor, said directing means having a regularly recurring cycle of movement to vary at definite periods the point of feed of the wire to said arbor.

3. A fence making machine comprising a stationary spiral member and a rotating arbor located within said member, said arbor having a wire strand wound thereon for the purpose of shaping said strand, and means for directing the feed of the wire strand upon said arbor, said directing means having a cycle of movement occurring once during a rotation of the arbor to vary the point of feed of the wire strand to said arbor, whereby a characteristic shape is imparted to the wire wound upon the arbor.

4. A fence making machine comprising a stationary spiral member, an arbor located within said member, means for imparting rotations to said arbor, wire directing means for directing the feed of wire to said arbor, said means comprising a pivoted arm having engagement with the wire immediately in advance of the arbor, and a cam for causing

the desired movements to be imparted to the pivoted arm.

5. A fence making machine comprising a stationary spiral member, an arbor located within said member, means for imparting rotations to said arbor, wire directing means comprising a pin having contacting engagement with the wire immediately in advance of the arbor, a disk having rotations in accordance with the rotations of the arbor, a cam formed in the disk, and means associated with the cam for causing desired movements to be imparted to the pin.

6. In a machine for forming a wire fence picket, a rotating arbor upon which the picket is formed, a spiral member surrounding the arbor for causing movement of the picket thereon, and means for changing the relative position on the arbor at which the wire is fed thereto, said means having movements in timed relation with the rotations of the arbor.

7. In a machine for forming a wire fence picket, a rotating arbor upon which wire is wound to form the picket, a spiral member surrounding the arbor for causing movement of the picket on the arbor in a certain direction, and means for directing the feed of the wire to the arbor, said means having a regularly recurring movement in a direction opposite to that of the movement of the picket on the arbor, to thereby change the point of feed of the wire to the arbor.

8. In a machine for forming a wire fence picket, a rotating arbor upon which the picket is formed, a spiral member surrounding the arbor for causing movement of the picket thereon, said member comprising spiral threads and providing a shoulder at its inner end at which the wire strand is fed to said arbor, and means for varying the point of feed of said wire from one side of the shoulder to the other.

9. A fence making machine comprising a stationary member and a rotating arbor located within said member, said member being shaped to provide spiral threads, a second member of spiral shape associated with said first mentioned member, said arbor having a wire strand wound thereon for the purpose of shaping said strand, and means for varying the feed of said wire to said arbor from one side of said second spiral member to the other side.

10. A fence making machine comprising a stationary member and a rotating arbor located within said member, said member being shaped to provide spiral threads and spiral openings, a second set of spiral threads positioned in said spiral openings, and means for directing the feeding of a wire strand to said arbor, said means functioning to feed said strand alternately to the respective sides of said second set of spiral threads.

11. A fence making machine comprising a

stationary member and a rotating arbor located within said member, said member being shaped to provide spiral threads and spiral openings, a second set of spiral threads positioned in said openings and terminating to permit a wire strand to be wound upon the arbor, and directing means for the wire functioning to direct the same to one side of the second set of spiral threads at said end and then to said other side.

Signed at Waukegan, Illinois, this 14th day of April, 1930.
